United States Patent Office

Des. 195,674
Patented July 16, 1963

195,674

CEILING TILE

Arthur W. Hopkins, Edgewater, N.J., assignor to The Flintkote Company, New York, N.Y., a corporation of Massachusetts

Filed Dec. 31, 1962, Ser. No. 73,022

Term of patent 14 years

(Cl. D18—2)

FIG. 1

FIG. 2

FIG. 1 is a plan view of the ceiling tile of the invention; and

FIG. 2 is a side elevational view taken along the lines 2—2 of FIG. 1 looking in the direction of the arrows.

I claim:

The ornamental design for a ceiling tile, as shown.
